GIMP GUIDING MECHANISM

Christiaan Joseph Marinus Benink, Heinrich Bungert, and Karl Kleemann, Kaiserslautern, Pfalz, Germany, assignors to G. M. Pfaff A.-G., Kaiserslautern, Pfalz, Germany

Application November 14, 1956, Serial No. 622,109

Claims priority, application Germany November 15, 1955

7 Claims. (Cl. 112—100)

The invention relates to a special arrangement in buttonhole sewing machines provided with a gimp guide which is secured to a guide bar which is movable in the direction of feed. The guide bar is moved against the effect of a spring from a predetermined end position into a predetermined starting position and locked prior to the start of the sewing work. In the area of changing of the direction of movement of the material presser frame the bar is again released and returns into the end position.

Gimp guides of this type are known. For adapting them to gimps of different thickness it is desirable that the gimp guide is adjustable with respect to the needle. Such adjustment is not possible in the known gimp guiding arrangements because the motion of the guide bar or of the gimp guide while changing from one side of the needle to the other side at the point of return of the movement of the material presser frame is constant. Besides, owing to the straight line movement of the guide bar, the known arrangements are only useable for machines where the material presser frame effects a transverse motion at the reversing points of the feeding movement in order to sew both edges of the buttonhole. They are not suitable for modern rapidly operating machines where the material presser frame executes merely a reciprocating movement in the direction of the machine arm by shifting the moving area of the needle bar for sewing the two edges.

It is an object of the invention to provide a gimp guide arrangement where the aforementioned shortcomings are avoided and which is universally applicable to machines which automatically sew around the edges of the buttonhole a plurality of times. In accordance with the invention this object is attained primarily in that the guide bar is arranged to effect a swinging movement in order to execute the evasion arc of the gimp guide around the needle at the reversing points of the longitudinal movements of the material presser frame and is at the same time supported for displacement longitudinally in a known manner, and in that the arc of evasion is adjustable as a result of the adjustability of the gimp guide at the guide bar as well as by cooperation of the guide bar with abutments serving for limiting the longitudinal movement of said guide bar as well as also for the adjustment of the magnitude of the lateral motions, and is adjustable also in its position relative to the needle.

It is a further object of the invention to provide a gimp guide where the moment of the release of the return motion around the needle is primarily adjustable by means of a cam provided upon a control disc.

It is still a further object of the invention to journal the guide bar in a pivot housing provided at the end of a lever pivotally journaled in the arm of the machine.

In accordance with a still further object of the invention the release of the locked guide bar is effected at the aforementioned cam by way of a guide and transfer lever with the aid of a pressure bar.

For the adjustment of the magnitude of the lateral deflection of the guide bar it is possible to arrange an ad-

2

justable transfer member between the control lever and the transmission levers.

In buttonhole machines which automatically sew around the edges of a buttonhole a plurality of times an electromagnet may be provided which after the first turn around the buttonhole effects the return of the guide bar to the starting position for each further peripheral sewing operation. The electromagnet may be controlled by a switch which is in turn controlled by an additional cam on the control disc.

Further features of the invention and details of the advantages provided by the invention will appear from the following description of the embodiments of the new gimp guiding means as illustrated by the accompanying drawings, where

Fig. 1 is an elevational view of a buttonhole sewing machine for single borderstitching of the buttonhole by means of the gimp guiding means in accordance with the invention as viewed from the operating side;

Fig. 2 is a perspective view of the opposite side of the machine taken obliquely from the front end;

Fig. 3 is a plan view of the gimp guiding means;

Fig. 4 is a partial cross-section along line IV—IV in Fig. 1;

Fig. 5 is a view on an enlarged scale illustrating the mounting of the abutment discs;

Fig. 6 is a rear view of the guide cam disc for the single borderstitching;

Fig. 7 is a rear view of the cam disc for double borderstitching;

Fig. 8 shows the arrangement of the end switch;

Fig. 9 is the arrangement of an electromagnet for returning the guide bar of the gimp guiding means, and

Fig. 10 is a section taken along line X—X in Fig. 9.

The sewing machine which comprises essentially a base plate 1, standard 2, arm 3 and head 4, is equipped in the customary manner with a guide disc 5 for controlling the longitudinal movements of the material presser frame 7 which is provided on the material presser lever 6. The control movements from the heart shaped cam groove 8 of the guide disc 5 are transmitted from slide lever 10 which supports a roller 9 and which is mounted for pivotal movement about a collar screw 11, by way of push rod 12 and bearing member 13, to the material presser lever 6. The bearing member 13 is secured to rod 14 which is mounted upon arm 3 of the machine.

On the rear surface of the guide disc 5 a guide ring 15 (Fig. 6) is formed in a known manner to provide the control movements for the needle bar oscillator 16 (Fig. 2) to shift the area of operation of the needle bar 17 for sewing the two edges of the buttonhole. The components for transmitting these control movements from the guide ring 15 to the needle bar oscillator 16 which are of known construction are not illustrated in the drawing to permit clearer illustration of the invention. The needle 18 is secured to the oscillator bar 17.

The material presser lever 6 is provided at its front end 19 with a guiding surface 20 of prismatic shape for the pressure roller 21 (Fig. 2) which is journaled on the pressure roll support 22, which in turn is secured to the material presser bar 23 biased by a spring 24. The rearward end 25 of the material presser lever 6 is enabled to cooperate with pressure screw 26 on the lifting lever 27 for the material presser. The latter is journaled on a stud 28 on the standard 2 and provided with a bore 29 at its free end which is engaged by a chain 30 which is in turn connected in a known manner with the operating member for the lifting lever 27.

Lifting lever 27 furthermore supports a roller 31 in coaxing engagement with a groove 32 of the grooved curve lever 33 which is pivotally secured to the standard

2 by means of a collar screw 34. Curve lever 33 is connected by way of a bar 35 and a crank 36 to shaft 37 which serves in a known manner for actuating the knife provided for cutting the bottom thread. Lifting lever 27 and thereby curve lever 33 are raised to the position illustrated in Fig. 4 by the action of a spring 38 when the operating member is released.

In accordance with the invention a gimp thread 39 (Fig. 1) is fed by way of a thread spanner 40 to a gimp guide 41 which is adjustably secured to the end of an arm 43 by means of a screw 42. The gimp guide 41 is provided at both ends with eyelet type thread guides 44 and 45 (Fig. 3). The arm 43 is secured by means of a screw 48 in a bore 46 provided in a chuck 47. The chuck 47 in turn is secured by means of screws 49 to a U-shaped support 50 which is mounted by means of screws 51 on a guide bar 52.

The guide bar 52 is mounted for longitudinal and pivotal movement in the pivot housing 53 (Fig. 2) of a double armed lever 55 pivotally mounted on a stud 54. For this purpose a slot 56 is provided in the guide bar 52 which is engaged by a pin 57 secured in a cylindrical guide member 58. This member is pivotally mounted in a bore 59 of the pivot housing 53 and thus constitutes the pivot axis of the guide bar 52. The pivot housing 53 is covered by plates 60 and 61 (Fig. 2) at the top and bottom sides which are held in place by screws 62, to prevent guide member 58 from dropping out.

The double armed lever 55 is biased by a spring 64 which is secured to the lever end 63 by means of a screw 65 and to the machine arm 3 by means of screw 66. At the upper end of arm 63 a pressure member 67 is securely held by means of a screw 68 which serves in a known manner for loosening the thread tensioner 69. A draw bar 71 is jointed by means of a collar screw 70 to lever 55 and is connected at its other end to the starting mechanism of the machine.

There is furthermore secured to guide bar 52 a support 72 (Fig. 3) by means of screws 51, which presents an abutment lug 73 and a forwardly and downwardly extending arm 74 (Fig. 2). The latter is provided with a pin 76 secured in a threaded bore 75 which pin projects into a bifurcated extension 77 of the roller support 22.

Support 72 is provided with a bore 78 (Fig. 3) which receives a guide member 80 provided with a threaded stud 79 and retained by means of a nut 81. The guide member 80 coacts with adjustable lateral abutments 82 and 83 provided in a small bearing chuck 85 secured to the head 4 by means of screws 84 (Fig. 2). A slot 86 in the chuck 85 defines two extensions 87 and 88, each having a bore 89 (Fig. 5) which is rotatably engaged by a threaded sleeve 90 having a slot 91. The sleeves 90 are each provided with an annular groove 92 which is engaged by a safety screw 93 having a pin-like projection 94 to prevent changes in position in axial direction and also rotation of the sleeves 90. The disc shaped abutments 82 and 83 are screwed in the threaded sleeves 90 by means of screws 95 and 96 and are each secured by means of a set screw 97 and 98.

In the slot 86 between extensions 87 and 88 of the chuck 85 an abutment member 99 is disposed having a rounded edge on one side and an angular bar 100 presenting a longitudinal slot 101 for the adjustable mounting by means of a screw 102 on the chuck 85. The abutments 82 and 83 are somewhat flattened along the side 65 which faces the abutment member 99 to insure against turning.

A further abutment disc 103 (Fig. 2) cooperates with the abutment nose 73 of the cam support 72 which disc has a bolt 104 received in an eye 105 on the chuck 85 and secured by means of a screw 106.

The guide bar 52 is biased by a spring 107 (Fig. 2) which is hooked to lugs 108 and 109 and which are provided by means of screws 110 and 111 on the guide bar 52 and on head 4, respectively. The spring tends to pull 75

the guide bar 52 either with its guide member 80 against the abutment member 99 or with its nose 73 against the abutment disc 103, depending on whether the gimp guide 41 is disposed before or behind the needle 18.

5 A roller 113 is mounted on a bolt 112 at the rear end of the guide bar 52 (Fig. 3) which roller is held by means of a safety ring 114. The roller 113 is associated with a slanted plane 116 (Fig. 2) provided on angular lever 115 and as the lever 115 moves downwardly it engages the plane and moves the guide bar 52 against the bias of the spring 107 in the direction of the standard 2. The angular lever 115 is secured by means of screws 117 to the draw bar 35 which, as described above, is actuated by the lift lever 27.

15 A pressure pin 119 disposed perpendicularly to the guide bar 52 is slidably mounted in two bearing lugs or brackets 118 and 118a (Fig. 3) extending downwardly from the arm 3 of the machine and is under the pressure of a spring 120 which is wound about the pin 119 and

20 rests with its ends against the bearing bracket 118 and against an adjusting ring 121 threaded upon the pin 119. The end of the pressure pin 119 which is remote from the guide bar 52 presses against the end of a lever 122 (Fig. 1) under the pressure of spring 120, which lever

25 is clamped with its split hub 123 by means of a screw 124 to the lower end of a pin 125 which is rotatably mounted in a portion 126 formed in the arm 3. A further lever 127 is secured by means of a screw 128 to the upper end of the pin 125, having a free end which coacts with an adjustable transfer member 129. The transfer member 129 is provided with a slot 130 for adjusting purposes, through which adjusting screws 131 extend and complete the connection with a double armed control lever 132.

30 The latter is rotatable about a collar screw 133 which is secured to a chuck 134 which is secured by means of screws 135 to arm 3. One arm 136 of the control lever 132 is provided with a set screw 137 to limit its area of rotation while its other arm 138 is provided with a lug 139 (Fig. 3) which projects into the path of rotation of a control cam 140 provided on the back of the control disc 5. The cam 140 is adjustably secured to the control disc by means of screws 141 which are received in an elongated slot 142 of a cam support 143 disposed concentrically with respect to the axis of

35 rotation of the control disc 5 (Fig. 6).

40 The guiding lever 52 is biased by a further spring 144 (Fig. 3) which holds the guide member 80 of the support 72 against the lateral abutments 82, 83 of the bearing chuck 85. The spring 144 is hooked at one end to a hook 145 which is fastened to the guide bar 52 and with its other end it engages a lug 146 which is fastened to the lever 122 by means of screw 124.

45 Before sewing identical button holes it is necessary to undertake the following adjusting operations:

Upon loosening screws 42 and 48 the height of the gimp guide above the material and the distance ahead of the needle for sewing the left button hole cord edge must be adjusted. Furthermore, the position of the gimp guide for sewing the left edge must be adjusted by axially moving the abutment disc 82. For this the counter screw 97 and the set screw 93 must be turned back, whereupon the threaded sleeve 90 can be rotated. As a result the abutment disc 82 moves in a direction toward or away from the machine head 4. The adjustment of the abutment disc 83 for adjusting the gimp guide 41 for sewing the left edge can be effected in a similar manner. The moment of the shifting of the gimp guide 41 after sewing the left edge can be adjusted by shifting the control cam 140 on the control disc 5. The magnitude of the lateral deflection of the gimp guide 41 at the return point can be set by adjustment of the transfer member 129 on the control lever 132. The deflection is increased by shifting the transfer member 129 toward the cam disc 5 and decreased by shifting the member in the opposite direction.

Furthermore, the length of the evasion arc can be raised

by adjustment of the abutment disc 103 on the chuck 85. For this purpose the screw 106 must be loosened whereupon the carrying bolt 104 can be displaced axially. Finally there is also the possibility of affecting the evasion path of the gimp guide 41 during the return movement of the guiding lever 52 by displacing the abutment member 99 from the end position to the starting position as the material presser frame 7 is raised.

The course of operations takes place in the following manner:

As the material presser lever 6 is operated for inserting the material to be sewed the roller 31 moves also the curve lever 33 downwardly so that the draw bar 35 and the angular lever 115 move downwardly. As a result the inclined abutment plane 116 of the angular lever 115 causes the guiding bar 52 to move against the tension of the spring 107 in the direction of standard 2 while the guide member 80 slides over the rounded edge of the abutment member 99 as a result of the possibility of laterally moving the guiding bar 52. As the material presser lever 6 is released the guiding bar 52 is no longer subject to the pull of the spring 107 because the guide member 80 is pulled by spring 144 into the niche formed by the two abutments 82 and 99 and is locked. Consequently, spring 107 continues to be tensioned. With this movement of guide bar 52 the gimp guide 41 effects a movement about needle 18, thus moving from the end position, i. e. that position which is attained after sewing the right or second edge to the position in front of the needle 18 in the direction of feeding for sewing the left edge. This position is considered to be the starting position. If the machine is now switched on in the usual manner, the material presser frame 7 begins to move in the direction of operation. At the return point of the movement of the material presser frame, i. e. at the end of the left edge, the lock on the guiding bar 52 is released by the control cam 140 on the control disc 5 by transmitting a control impulse to bar 52 by way of control lever 132, transfer levers 122 and 127 and pressure pin 119. As a result the guiding bar 52 swings laterally, permitting guide member 80 to slide from the abutment 99 and to follow the pull of spring 107. The longitudinal movement of the guide bar 52 is limited by the engagement of the abutment 103 by the lug 73. During this movement of the guide bar 52 the gimp guide 41 moves from the position behind the needle 18, as related to the new opposite feeding direction of the material presser bar 7, and location "left edge," into the position in front of the needle and location "right edge."

Now the right edge is sewed and the machine automatically stops with the needle raised after sewing the lock.

As the material presser frame is raised for removing the material the guide bar 52 and the gimp guide 41 are returned to the initial position as described above.

For button hole machines which automatically sew around the edges of the button hole a number of times, for example twice, an additional means is required which is constructed as described hereinafter.

In lieu of pin 112 the guide bar 52 is provided with a longer pin 147 (Fig. 10) which supports an additional roller 148. An abutment 149 (Fig. 9) cooperates with this roller which is formed on an arm 150 of a double lever 151 which is journaled in a conformation in the arm 3 of the machine on a pin 153 to which it is fastened by means of a screw 152 and which is secured by a screw 154. The other arm 155 of lever 151 is offset and bifurcated at its end 156. A collar screw 157 engages the fork 156 to which is secured a bifurcated member 158, which in turn is provided on the armature 160 of an electromagnet 161 by means of screws 159. A pressure spring 162 is disposed between the bifurcated member 158 and the housing of the magnet.

Electromagnet 161 is provided with angular shaped

mounting lugs 163 which are secured to the machine arm 3 by means of screws 164.

A control disc 165 (Fig. 7) designed for dual circumferential edge stitching of the button hole is provided in place of a single cam 140 as in the first embodiment, with two adjustable cams 166 and 167 for releasing the locked position of the guide bar 52 by way of control lever 132. A further adjustable cam 168 is provided having a path of operation into which extends an abutment 170 provided on one end of an angular control lever 169 (Fig. 8). The control lever 169 is rotatably journaled on a collar screw 171 secured to the machine arm 3.

A switch bar 172 of a switch 173 is provided in the path of the other end of control lever 169 and the switch is secured to the machine arm 3 by means of screws 175. The range of movement of the control lever 169 is limited by a stop pin 176 on arm 3. The switch 173 is connected in series with the electromagnet 161 and is supplied with current from a source (not shown).

The operation of this arrangement is effected by lifting the material presser frame 7 and as in the first embodiment the guide bar 52 is moved to the starting position, thus tensioning spring 107. Upon sewing the first cord the control cam 166 releases the guide bar 52 thus swinging the gimp cord guide about the needle.

At the end of the second edge the machine does not automatically stop, but it starts the second course around. Immediately before that the cam 168 actuates the end switch 173 by way of control lever 169, thus closing the circuit of electromagnet 161. The latter attracts and swings double armed lever 151 counterclockwise (Fig. 9). This returns the guide bar 52 and thus also the gimp guide 41 to starting position in the same manner as in the first embodiment by means of the lift lever 27 for the material presser. The button hole is now edge stitched in the same manner a second time except that after sewing the first cord the guide bar 52 is released by the operation of cam 180 which is displaced 180°. Upon completion of the second cord and the end lock the machine stops automatically.

Having now described our invention in connection with the embodiments illustrated in the drawings we do not wish to be limited thereto but what we desire to protect by Letters Patent is set forth in the appended claims.

We claim:

1. Gimp guiding means for button hole sewing machines of the type including a needle supported by a needle bar at the head of the machine, a movable material presser frame and a reciprocating mechanism therefor, a gimp guide supported by a guide bar movable longitudinally in the direction of material feeding and having a starting position and an end position, a first spring biasing said guide bar toward said end position, means cooperating to lock said guide bar and guide in starting position, means including said reciprocating mechanism operative to release and return said guide bar to the end position in response to reversing of movement in the direction of the material presser frame, said guide bar being supported for lateral movement and including means operative to effect an evasion arc of said gimp guide about the needle, said means comprising lateral abutment and catch means and a second spring exerting lateral pull on said guide bar coacting to retain said bar in the position for locating said gimp guide in said starting position, and end abutment means coacting with said first spring means to return said bar to the position for locating said gimp guide in said end position, said lateral abutment and catch means and said end abutment means being adjustable to vary the extent of lateral movement and forward movement, respectively, of said guide bar and said gimp guide, and said gimp guide being adjustable relatively to said guide bar for adjustment of the position of said guide relative to said needle.

2. Gimp guiding means in accordance with claim 1, wherein said reciprocating mechanism includes a cam disc

and a presser bar supporting said presser, said cam disc being provided with an adjustable cam member operatively connected by a lever and pin mechanism to said guide bar to effect release from said catch means.

3. Gimp guiding means in accordance with claim 2, wherein said guide bar is mounted in a pivot housing supported by a two armed lever pivotally mounted on the housing of the machine.

4. Gimp guiding means in accordance with claim 3 including a pressure pin extending from said guide bar transversely of the machine for engagement of a control lever which is in operative engagement with said cam disc for engagement by said adjustable cam to effect release of said guide bar from locked position.

5. Gimp guiding means in accordance with claim 4 wherein said lever and pin mechanism is associated with and includes an adjustable transfer member movable on a lever adapted to limit the magnitude of lateral movement of the pin and of said guide bar.

6. Gimp guiding means in accordance with claim 5, wherein said guide bar is operatively connected with a mechanism including an electro magnet adapted to return said gimp guide to starting position upon completion of one peripheral sewing operation around the button hole.

7. Gimp guiding means in accordance with claim 6, including a switch associated with said electro magnet and an additional cam on said disc adapted to operate said switch.
